W. E. LEE

SPARK PLUG

Filed Jan. 28, 1920

Inventor -
William E. Lee

g Cook & McCaulay 975

UNITED STATES PATENT OFFICE.

WILLIAM E. LEE, OF ST. LOUIS, MISSOURI, ASSIGNOR OF ONE-HALF TO LENDALL C. CROSBY, OF ST. LOUIS, MISSOURI.

SPARK PLUG.

Application filed January 28, 1920. Serial No. 354,654.

To all whom it may concern:

Be it known that I, WILLIAM E. LEE, a citizen of the United States of America, a resident of the city of St. Louis, in the State of Missouri, have invented certain new and useful Improvements in Spark Plugs, of which the following is a full, clear, and exact description, reference being had to the accompanying drawings, forming a part 10 of this specification.

This invention relates to improvements in spark plugs, the main object being to provide a spark plug having a sparking terminal adapted to move independently of 15 the holder whereby it is secured, so as to expose different areas at the spark gap.

In the preferred form of the invention, the sparking terminals are in the form of balls rotatably mounted in sockets, and 20 adapted to turn in response to vibrations to which the plug is ordinarily subjected in service. These balls have continuous, endless sparking surfaces, and when in service the vibrations of the engine result in a corresponding vibratory movement at the balls, 25 whereby an irregular, jerky, rotary motion is transmitted to the balls. As a consequence, the balls turn in their supporting 30 sockets to expose different sparking surfaces at the spark gap. The sockets are preferably provided with scraping edges engaging the rotary balls to remove carbon therefrom. It will, therefore, be understood that the balls are repeatedly shifted 35 to expose different surfaces at the spark gap, thereby avoiding trouble which has heretofore resulted from accumulations of carbon on the sparking points.

Fig. I is a side elevation of a spark plug 40 embodying the features of this invention.

Fig. II is an enlarged view, partly in section, illustrating the lower portion of the plug.

Fig. III is a bottom view of the plug 45 with the stem at the lower end thereof shown in section.

To illustrate the invention, I have shown a spark plug wherein the outer electrode comprises a hollow shell 1, an L-shaped stem 2 having a vertical arm screwed into the lower end of said shell and provided with a socket 3 in which a ball 4 is mounted. The lower portion of stem 2 is bent to provide a horizontal arm, said arm being

threaded to receive the socket 3. An insulator 5 is secured in the shell 1. The lower portion of shell 1 is threaded to provide means for securing the plug to an engine cylinder.

The inner electrode comprises a wire, or 60 rod, 6 threaded at its upper end to receive a nut 7 whereby a wire may be secured to the plug, and a socket 8 which may be integrally connected to the lower end of rod 6. A ball 4' is mounted in the socket. Tongues 9, formed at the open end sockets 65 3 and 8, are bent to confine the balls in the sockets, and these ends have scraping edges which engage the balls.

It will be observed that the balls 4 and 4' 70 form the terminals of the inner and outer electrodes, and that these balls are separated to provide a spark gap between them. Although the tongues 9 are bent inwardly to contact with and confine the balls, said 75 tongues do not rigidly secure the balls in the sockets. The balls are free to turn in response to vibrations to which the sockets are subjected in service, and an irregular rotary motion is therefore imparted to the 80 balls, as previously pointed out, to expose clean sparking surfaces at the spark gap, at the same time removing carbon from the 85 surfaces of the balls, the carbon being removed by the scraping edges of the tongues 9.

I claim:

A spark plug having an outer electrode comprising a shell, an L-shaped stem having a vertical arm screwed into said shell 90 and a horizontal arm extending from said vertical arm, a socket screwed onto said horizontal arm, a terminal in the form of a ball closely confined in said socket but free to turn in response to vibrations of 95 said arm and socket, said socket being provided with scraping edges maintained in engagement with the closely confined ball, and an inner electrode comprising a rod having a socket at one end, a terminal ball 100 closely confined in the last mentioned socket but free to turn therein, the last mentioned socket having scraping edges maintained in engagement with the last mentioned ball.

In testimony that I claim the foregoing 105 I hereunto affix my signature.

WILLIAM E. LEE.
